UNITED STATES PATENT OFFICE.

JAMES MCNEIL, OF ALLEGHENY, PENNSYLVANIA.

VALVE-GEAR FOR EXPLOSIVE-ENGINES.

SPECIFICATION forming part of Letters Patent No. 682,880, dated September 17, 1901.

Application filed February 28, 1901. Serial No. 49,274. (No model.)

To all whom it may concern:

Be it known that I, JAMES MCNEIL, a citizen of the United States, residing at Allegheny, in the county of Allegheny and State 5 of Pennsylvania, have invented new and useful Improvements in Gas-Engines, of which the following is a specification.

This invention relates to gas-engines, and the primary object thereof is to improve and 10 simplify the engine by dispensing with all spring-actuated valves, tripping mechanisms, &c., usually employed for controlling the admission and exhaust ports, and in lieu thereof I provide a rotary double valve adapted to 15 be actuated by the engine-shaft.

The invention consists in the novel structural features and combination and arrangement of parts hereinafter fully described and claimed, and illustrated by the accompanying 20 drawings, wherein—

Figure 1 is a view, partly in elevation and partly in section, of an engine embodying my improvements. Fig. 2 is a similar view of the upper portion of the engine, the sectional 25 portion of said view being taken on line 2-2 of Fig. 1. Fig. 3 is a view similar to Fig. 2, taken on line 3-3 of Fig. 1. Fig. 4 is a plan view, the cap-plate of the valve-casing being removed. Fig. 5 is a detail view of the valve. 30 Fig. 6 is a diagrammatic view illustrating the operation of the valve.

Referring to the drawings, 2 represents the cylinder; 3, the crank-shaft; 4, the piston-rod, and 5 the piston.

35 6 is the cylinder-head, and cast integral therewith is the elongated and transversely-circular valve-casing 7. Rotatably mounted within this casing is the cylindrical valve 8, having at one end a stem 9, carrying sprocket-wheel 10, and leading from this wheel is chain 11 to wheel 12 on short shaft 13, said shaft also carrying gear 14, which meshes with pinion 15 on crank-shaft 3. The valve-casing and cylinder-head are formed with the vertically-aligning inlet-ports $a a'$ and corresponding exhaust-ports $b b'$, and coöoperating with these ports are inlet-port c and exhaust-port d of valve 8. All of said ports are of corresponding length and width. The top of valve- 45 casing 7 is faced off to receive cap-plate 16, formed with tapered ports 17, with which the

inlet and exhaust pipes 18 and 19 connect. Cylinder 2 is constructed with the usual water-jacket 2', and head 6 is cored at 20 to provide for free circulation of water.

55

The operation is as follows: Wheel 10 being double the diameter of wheel 12 and gear 14 double the diameter of pinion 15, the engine crank-shaft makes four revolutions while valve 8 is making one, and in the same interval the piston makes eight strokes. An engine of the four-cycle type being here shown, a complete operation is effected by four strokes of the piston or while valve 8 is making half a revolution. With piston 5 and 60 valve 8 in positions shown in Figs. 1, 2, and 3, all of said views corresponding, the piston has completed its fourth or exhaust stroke and is about to begin the charging stroke. At this point in the operation valve exhaust-port d has just passed from in line with fixed ports $b b'$, as seen in Fig. 2, and valve inlet-port c is about to uncover fixed ports $a a'$, as in Fig. 3. Ports c and d of the valve are thus arranged so that either the inlet or exhaust will be completely closed before the other starts to open. 65 As before stated, ports a, a' , and c are of corresponding width, as are also ports b, b' , and d . Hence the periphery of valve 8 advances a distance equal to double the width of port c or of port d at each stroke of the piston. Thus on the exhaust-stroke fixed ports $b b'$ and port d are first completely opened by the first half of the stroke and then completely closed by the latter half thereof. On the next or charging 70 stroke said operation is repeated by ports a, a' , and c . During the third or compression stroke and the fourth or explosion stroke all ports are closed; but at the completion of the fourth stroke exhaust-port d of valve 75 8 is again ready to register with fixed ports $b b'$ as soon as the next or exhaust stroke begins. In diagram, Fig. 6, the dotted lines of port d indicate its position at the beginning of the exhaust-stroke and the full lines at the completion of said stroke, the latter 80 position being indicated by letter E. At the completion of the first or charging stroke its position is indicated by F, at the completion of the compression-stroke by G, and completion of the explosion-stroke by H. The valve 8 is thus double in that it controls both the 85 90 95 100

inlet and exhaust and double acting in that the valve-ports operate alternately in reverse positions.

While I have thus shown and described the 5 valve and its operation with considerable exactness, it will be understood that this is only an embodiment of the principles underlying the invention, which may be practiced or applied in a number of ways without departing 10 from the spirit and scope of the invention.

Having thus fully described my invention, what I claim as new, and desire to secure by Letters Patent, is—

1. The combination of a cylinder, a cylindrical valve-casing formed with cylinder-ports a' and b' , the casing having two ports a and b diametrically opposite ports a' and b' respectively, the ports a a' and b b' being in lines parallel with the axial line of the casing, a cylindrical valve formed with through-and-through ports c and d in the planes of ports a a' and b b' respectively ports c and d being disposed in different radial lines, and inlet and exhaust connections for ports a and 25 b , substantially as shown and described.

2. The combination of a cylinder, a piston, a crank-shaft operatively connected to the piston, a cylindrical valve-casing formed with cylinder-ports a' b' the casing also being formed with ports a b diametrically opposite 30 ports a' b' , a cylindrical valve formed with the through-and-through radial ports c d , all of said ports being of corresponding width and the peripheral length of the valve being sixteen times the width of any one of said ports, the distance between lines extending longitudinally of the valve on the periphery thereof and intersecting adjacent sides of ports c and d being the same as the width of one of said ports, and mechanism for imparting 40 one revolution to the valve for every four revolutions of the crank-shaft, substantially as shown and described.

In testimony whereof I have hereunto set my hand in presence of two subscribing witnesses.

JAMES MCNEIL.
